UNITED STATES PATENT OFFICE.

CAMPBELL C. CARPENTER, OF EAST CLEVELAND, OHIO, ASSIGNOR TO WILLARD STORAGE BATTERY COMPANY, OF CLEVELAND, OHIO, A CORPORATION OF WEST VIRGINIA.

ELECTROLYTIC RECTIFIER.

Application filed July 15, 1922. Serial No. 575,374.

This invention relates to improvements in electrolytic rectifiers, and has for its chief object to provide a rectifier which will permit the use of a small amount of solution. 5 Further the invention aims to provide a rectifier which is small and compact and has provision for preventing abnormal rise of temperature.

The invention may be briefly summarized 10 as consisting in certain novel details of construction and combinations and arrangements of parts which will be described in the specification and set forth in the appended claims.

15 In the accompanying sheet of drawings wherein I have illustrated an embodiment of the invention which operates with high efficiency, Fig. 1 is a side elevation of the rectifier; Fig. 2 is a vertical sectional view of the 20 same with a portion in elevation; and Fig. 3 is a top plan view.

My improved rectifier includes a cylindrical chamber or container 10 for the electrolyte, this container being preferably 25 formed of lead and constituting the conducting electrode of the device. A film forming electrode, preferably formed of aluminum is shown at 11, this electrode in this instance extending laterally into the container 10 and 30 being held in place by having its outer end portion 11^a fitted into a tapered plug 12 which may be of rubber, the latter in turn fitting into a lead bushing 13 soldered to the cylindrical wall of the container.

35 Extending up from the flat top of the container 10 is a dome 14 forming a gas collecting chamber, and extending through and secured in the top of this dome 14 is a vent tube 15. The dome 14 can be conveniently 40 provided by forming an opening in the top of the container 10 and soldering the dome to the marginal wall of this opening, this dome, vent tube and other parts being preferably formed of lead, and the vent tube is 45 preferably soldered in an opening formed in the top of the dome 14. It is to be noted that the bottom of the vent tube is on a level with the bottom of the dome 14 or top of the container 10, and that the upper end of the vent 50 tube is some distance above the dome.

Secured to the top of the container 10 and at its lower end soldered to the latter is a stand pipe 16 which may be of lead and which surrounds and is arranged concentrically with respect to the dome 14 and vent tube 15 and extends up a short distance above the top of the latter. This stand pipe is somewhat larger in diameter than the dome 14 so that there is an annular space between the two, and this stand pipe which has no direct connection at the bottom with the container or with the dome, forms an auxiliary chamber for the electrolyte. 55

Surrounding the stand pipe 16 there is a coil 17 also preferably formed of lead. The 60 lower end of the coil communicates at 18 with the space or chamber in the stand pipe 16, the point of connection between the lower end of the coil with the stand pipe being a short distance above the top of the electrolyte 65 container 10. The top of the coil 17 is a short distance below the top of the vent tube 15, and at its upper end the coil is connected by a downwardly extending tube or branch 19 forming a continuation of the coil with the 70 electrolyte container 10, the point of connection between the tube 19 and the container 10 being indicated at 20.

Any suitable electrolyte commonly employed in rectifiers may be utilized. The 75 electrolyte is poured into the stand pipe 16 and as the level rises in the stand pipe it gradually fills the coils 17 from the bottom, the electrolyte entering the coil at 18, and as soon as the level of the electrolyte in the stand pipe 80 rises above the coil it passes from the top of the coil down the tube 19 into the container 10. The electrolyte is supplied in this manner until the container and a portion of the dome 14 are filled, and when the electrolyte 85 has risen in the dome to a definite height depending upon the level of the electrolyte in the stand pipe, i. e. when the maximum amount has been supplied through the coil and tube 19, filling is discontinued, the electrolyte then standing in the stand pipe at a 90 level slightly above the top of the coil.

When the rectifier is then connected into a circuit and is used for the rectification of alternating currents, as for example, for charge- 95 100

ing a battery, gas is evolved, and though a slight amount may pass out through the vent tube, the major portion passes up into the gas collecting chamber or dome 14, and as 5 the gas collects therein it gradually displaces the electrolyte, forcing it down into the container 10, back and through the tube 19 around the coil 17 and into the stand pipe 16. The collection of gas in the dome and the displacing 10 of the electrolyte with its circulation through the tube and coil continues until the level of the electrolyte reaches the bottom of the vent tube 15, and when this occurs the gas collected in the dome and now under some 15 pressure suddenly finds an escape through the vent tube 15, and when once the outlet is established, that outlet is maintained until substantially the entire amount of gas in the dome escapes and the dome is again filled 20 with electrolyte.

While this is occurring, the liquid again runs back through the coil and tube into the container 10, entering the latter at 20. Immediately thereafter the gas begins again to 25 collect in the dome, gradually displacing the electrolyte and forcing it through the tube 19 and coil 17 into the stand pipe, and when the level reaches the bottom of the vent tube there is again a sudden and substantially complete 30 release of the gas and a quick return of the electrolyte to its former level.

This transference of electrolyte from the container 10 through the coil into the stand pipe by the collection of gas in the dome and the sudden escape of the gas with consequent quick return of the electrolyte takes place intermittently. The effect of this is to maintain a constant cooling of the electrolyte which prevents an abnormal rise in temperature, and 40 enables the rectifier to be operated at maximum or substantially maximum efficiency with the use of a small amount of electrolyte.

In other words, by my improvements above described I have provided a small and compact rectifier requiring only a relatively small amount of solution with ample provision against the rise of temperature and consequent drop in efficiency and rapid deterioration which would otherwise take place.

Having described my invention, I claim:

1. An electrolytic rectifier comprising an electrolyte chamber containing a film forming electrode, an auxiliary chamber extending upwardly from the top of the electrolyte chamber for electrolyte, a tube connecting said chambers, said first chamber having a portion at the top thereof extending into the auxiliary chamber wherein gas is collected so as to gradually drive part of the electrolyte into the second named chamber, and means for causing the sudden escape of the gas so as to permit the return of the electrolyte to the first named chamber.

2. An electrolytic rectifier comprising a body having two chambers including a main

electrolyte chamber and an auxiliary electrolyte chamber rising therefrom, a cooling coil connecting said main and auxiliary chambers, said main chamber having a gas collecting dome at the top thereof, and a vent tube extending down through the dome and having its open lower end adjacent the bottom of the dome.

3. An electrolytic rectifier comprising a body having two chambers including a main electrolyte chamber having a film forming electrode and, an auxiliary chamber rising therefrom, said first chamber having a gas collecting portion, a vent tube for the main electrolyte chamber extending through said auxiliary chamber and through the gas collecting portion of the main chamber and having an open lower end, and a cooling coil connecting the two chambers.

4. In an electrolytic rectifier, a main electrolyte chamber having a film forming electrode and provided with a gas collecting portion, an auxiliary electrolyte chamber rising from the main chamber, a vent tube extending through said auxiliary chamber and through the gas collecting portion of the main chamber, and a cooling coil surrounding the auxiliary chamber and having one end communicating with said auxiliary chamber and its other end communicating with said main chamber.

5. An electrolytic rectifier comprising a main electrolyte chamber having a gas collecting dome at the top, an auxiliary electrolyte chamber extending up from the main chamber and surrounding said dome, a vent tube extending through said dome to substantially the bottom thereof and arranged within said auxiliary chamber, and a cooling tube connecting said chambers.

6. An electrolytic rectifier comprising a main electrolyte chamber having a gas collecting dome at the top, an auxiliary electrolyte chamber extending up from the main chamber and surrounding said dome, a vent tube extending through said dome to substantially the bottom thereof and arranged within said auxiliary chamber, and a coil surrounding said auxiliary chamber and at its lower end connected to the lower part of said auxiliary chamber and at its upper end connected to said main chamber.

7. An electrolytic rectifier comprising a main electrolyte chamber having a gas collecting dome at the top, an auxiliary electrolyte chamber extending up from the main chamber and surrounding said dome, a vent tube extending through said dome to substantially the bottom thereof and arranged within said auxiliary chamber and a passage-way for electrolyte communicating with the main chamber below the dome and leading to the auxiliary chamber.

8. An electrolytic rectifier comprising a main electrolyte chamber having a gas col-

lecting dome at the top, an auxiliary electrolyte chamber extending up from the main chamber, a vent tube extending through said dome to substantially the bottom thereof, and
5 a coil surrounding said auxiliary chamber and connected at one end to the auxiliary chamber and at its other end to said main chamber.

In testimony whereof, I hereunto affix my
10 signature.

CAMPBELL C. CARPENTER.
